United States Patent Office

Des. 214,626
Patented July 8, 1969

214,626

OPTICAL PAGE READER

Collan B. Kneale, Dwayne E. Sylte, Ray B. Wheeler, and Frank Wilkey, Jr., Rochester, Minn., assignors to International Business Machines Corporation, Armonk, N.Y., a corporation of New York

Filed July 15, 1968, Ser. No. 12,773

Term of patent 14 years

Int. Cl. D14—02; D16—08

U.S. Cl. D26—5

FIG.

FIG. 3

FIG. 2

FIG. 1 is a perspective view of an optical page reader showing our new design;

FIG. 2 is a front elevational view thereof;

FIG. 3 is a rear elevational view thereof;

FIG. 4 is a top plan view thereof;

FIG. 5 is a left side elevational view thereof;

FIG. 6 is a right side elevational view thereof.

We claim:

The ornamental design for an optical page reader, as shown.
